UNITED STATES PATENT OFFICE.

JOHN J. LYTH, OF VALLEYFIELD, QUEBEC, CANADA.

APPARATUS FOR MOIRÉ-FINISHING CLOTH.

Application filed December 7, 1923. Serial No. 679,222.

This invention relates to improvements in apparatus for imparting moiré finish to cloth and for other purposes, and the primary object of the invention is to enable the desired 5 finishing operation to be conducted at a high rate of speed.

A further object is to provide for a practically infinite variation and control of the pattern produced.

10 A still further object is to provide a moiré finishing apparatus designed as an attachment to existing calendering machines, thereby to reduce the cost of installation as much as possible.

15 Various other objects and advantages may be ascertained from the following description.

Briefly speaking, the apparatus comprises a pair of cloth shifting members over which 20 the two layers of cloth to be finished pass into the nip of calender rolls and by axial movement of the members, the two layers of cloth are relatively oscillated in their respective planes, so that the threads thereof 25 cross and recross one another as they enter the nip of the calender rolls to the end that, by the pressure of the rolls, the threads of each layer are caused to make an impression on the other layer, imparting the desired 30 moiré finish or watered effect. These cloth shifting members may be loose rolls receiving rotary motion from the movement of the cloth and at any event are moved back and forth in their axial direction by any suitable driving means which may be regulated 35 at the will of the operator to bear any desired relation to the lineal speed of the cloth. In the embodiment of the invention herein illustrated and described, the driving 40 means employed is a fluid pressure motor, but it will be understood that other means which will permit of the desired speed regulation may be employed.

In the drawings which illustrate the 45 invention:

Fig. 1 is a front elevation of the device partly in section.

Fig. 2 is a plan view corresponding to Fig- 50 ure 1, also partly in section.

Fig. 3 is an end elevation of the motor.

Fig. 4 is a section of the motor controlling 55 valve on the line 4-4, Figure 3.

Referring more particularly to the drawings, 11 designates a pair of cloth shifting members of any suitable construction ar- 55 ranged in spaced relation, usually in par-

allelism. In the preferred construction illustrated each shifting member comprises a central spindle 12, a tubular roll 13 together with intermediate and end supports 60 14 and 15 respectively for the roll, the latter holding the roll between them through the operation of nuts 16 screwed on the spindle, or other suitable means.

Preferably the shifting members are rotat- 65 ably mounted, in which case the roll bodies 13 may be tightly clamped between the end supports 15. If, however, it is not desirable to rotatably mount the spindles 12, the roll bodies may be rotatable between their end 70 supports 15.

In the preferred construction a base and guide 17 is provided at one end of the device in which the spindles are reciprocatably and rotatably mounted. At the opposite end of 75 the device a cylinder block 18 is provided containing pistons 19 in which the ends of the spindles are rotatably and non-recipro- catably mounted. Operative connection be- 80 tween the spindles and pistons may be effected in any suitable way, for example by means of split pins 19^a in the pistons en- gaging circumferential grooves 12^a in the spindles.

The base 17 carries one or more rockers 20 85 pivotally related thereto, the arms of which are connected by links 21 with the ends of the spindles to the end that if either spindle is moved axially in one direction the other spindle will be moved axially in the opposite 90 direction.

Preferably the links 21 are arranged in pairs with recessed or apertured yokes 21^a between them in which the ends of the spindles are rotatably mounted. A con- 95 venient manner of mounting embodies coni- cal recesses in the yokes in which recesses the pointed ends of the spindles bear. This arrangement renders the entire end areas of the spindles available as thrust surfaces. If 100 desired the connection may be similar to that used at the opposite ends of the spindles.

Means may be provided for adjusting the spindles in their axial direction so as to regulate the relation of the pistons 19 with 105 the cylinder block. In the embodiment herein illustrated this adjusting means comprises a slide 22 mounted in a guide slot 22^a in the base 17 and movable in said slot in the axial direction of the rolls. The posi- 110 tion of the block is determined by any suitable means, such as a rod 23 threaded into

the support upon which rod the slide is revoluble but nonreciprocatable. The rocking lever or levers 20 are pivotally mounted upon the slide so that by movement of the rod 23 the slide, levers, rolls and pistons are simultaneously moved all in the same direction. In some installations such an adjustment will be unnecessary but in many cases, particularly where the device is attached to an already existing calender, the adjusting device may be found very convenient to adjust the device according to the width between frames of the calender and at the same time to obtain sufficient entry of the pistons into the cylinders on the exhaust stroke without blocking the ports.

The cylinder block is provided with a pair of bores 24 to receive the pistons 19, and also with a valve chamber 25 provided with an exhaust outlet 26 at one end and provided at the opposite end with a valve stem guide 27. Each of the bores 24 is closed at the end remote from the rolls and at the closed end a port 28 is provided communicating with a corresponding port 29 in the valve chamber. The ports 29 are spaced in the axial direction of the chamber and a motive fluid inlet 30 is provided intermediate these ports. A valve 31 is provided in the chamber having a passage 32 adapted to establish communication between either port 29 and the inlet 30. The valve may be of any suitable type but is preferably of the piston type illustrated and is operated by a stem 33 adjustably connected to a bracket 34 clamped to one of the rolls. The valve is obviously designed to simultaneously uncover one port to the inlet and one to the exhaust and upon reciprocation to reverse the connections thus established so as to admit motive fluid to the cylinders alternately and permit exhausting of spent motive fluid from the cylinders. When a valve stem guide 27 or other means closing one end of the valve chamber is used a passage 35 must be provided through the valve to establish communication between the exhaust outlet 26 and the port 29 most remote therefrom. If, however, both ends of the chamber are open this passage will be unnecessary.

A very convenient method of forming passages between the ports 28 and 29 is illustrated and embodies the provision of the valve chamber in a member separate from the cylinder block. The ports 28 may then extend in straight lines from the cylinder bores to the outer surface of the block and the ports 29 in straight lines from the valve chamber to the outer surface. Grooves 36 may then be formed in either member to form, when the parts are assembled, the necessary connecting passages. This method of manufacture is particularly desirable in apparatus of this character where the ports and passages are of necessity small and very

difficult to form by usual foundry methods and impossible to satisfactorily clean out.

The operation of the device is as follows:—Motive fluid, for example compressed air, is supplied to the valve and is thereby admitted to the cylinders alternately. The fluid when admitted to a cylinder drives out the piston therein and causes axial movement of the connected roll or cloth directing element. This movement is communicated through the rocking lever 20 to the other cloth directing element, which is thereby moved oppositely to the first. The piston of the second element enters the cylinder and expels expanded motive fluid from the cylinder through the valve to the outlet 26. The relatively opposite reciprocation of the rolls causes the two layers of cloth 38 between the rolls and the nip of the calender rolls 37 to be oscillated relatively in opposite directions. The amount of oscillation or angular movement of each layer of cloth from the normal line of movement is quite small and in any case not sufficient to cause wrinkling. By moving each of the two layers of cloth relatively in opposite directions a very slight angular movement of each layer produces the necessary relative angular displacement for satisfactory patterning. The construction employed enables the rolls to be reciprocated at high speed and as a result enables the cloth to be passed over the rolls and through the calender at much higher lineal speed than is possible with existing moiré finishing apparatus. As a result the finishing operation may be performed at much lower cost than heretofore. In addition to the foregoing the speed of reciprocation of the rolls may be regulated independently of the speed of the cloth by controlling the amount of motive fluid so as to vary the pattern as desired.

While a preferred embodiment of the apparatus has been described and illustrated, it will be understood that numerous alterations may be made without departing from the spirit of the invention, for example, a different type of motor may be used or double acting motors which will enable elimination of the rocking connection between the rolls. Another type of roll construction may also be adopted but that illustrated is preferred on account of its light weight and consequent reduction of the factor of inertia which must be considered in any rapidly reciprocating device. It will therefore be seen that one of the essentials of this invention is the provision of means to oscillate or move two layers of cloth relatively in opposite directions.

While the apparatus has been described in connection with moiré finishing, it will be understood that it may be used for other purposes. For example, the apparatus may be employed for breaking cloth by passing

the cloth back and forth over the rolls, a number of the devices being preferably employed.

Having thus described my invention, 5 what I claim is:—

1. A cloth treating apparatus comprising in combination with the calendering machine a pair of cloth directing elements over each of which a layer of cloth may pass into the 10 nip of the calender rolls, connection between said elements to cause relatively opposite reciprocation thereof in their axial direction thereby to relatively oscillate the two layers of cloth passing between said elements 15 and the calender, and fluid pressure motors connected to the elements to move both in the same direction, the said motors including valve mechanism to secure alternate operation of the motors.
2. A cloth treating apparatus comprising a pair of cloth directing elements reciprocatable in their axial directions, a motor at one end of each element in axial alignment therewith to move the elements in one 25 direction said motors including valve mechanism to secure alternate operation of the motors, and connection between the elements at the opposite end to secure relatively opposite movement thereof and expulsion of 30 spent motive fluid from the inoperative motor.
3. A cloth treating apparatus comprising a pair of cloth directing elements reciprocatable in their axial directions, a piston at 35 one end of each element, a cylinder block receiving the pistons and supporting the elements at one end, valve mechanism to control flow of motive fluid to and from the cylinders operatively connected to one of the 40 elements, a guide supporting the elements at the opposite ends, a rocking lever pivotally related to the guide and link connection between the ends of the lever and the adjacent ends of the elements.
4. A cloth treating apparatus comprising a pair of cloth directing elements reciprocatable in their axial directions, a piston at one 45 end of each element, a cylinder block receiving the pistons and supporting the elements at one end, valve mechanism to control flow of motive fluid to and from the cylinders operatively connected to one of the elements, a guide supporting the elements at the opposite ends, a rocking lever pivotally related to the guide and link connection between 50 the ends of the lever and the adjacent ends

of the elements, and a support for the rocking lever adjustably mounted in the guide to determine the relation of the pistons to the cylinder block.

5. A cloth treating apparatus comprising a pair of cloth directing rolls reciprocatable in their axial directions, a piston rotatably related to and in axial alignment with each roll at one end thereof, a pair of cylinders receiving the pistons, a valve common to the two cylinders to control flow of motive fluid to and from the cylinders, operative connection between the valve and one of said rolls, a guide slidably and rotatably supporting the remaining ends of said rolls, a thrust bearing for each roll, a rocking lever carried by the guide, and links connecting said bearings to the ends of the lever.

6. A cloth treating apparatus comprising a pair of cloth directing rolls reciprocatable in their axial directions, a piston rotatably related to and in axial alignment with each roll at one end thereof, a pair of cylinders receiving the pistons, a valve common to the two cylinders to control flow of motive fluid to and from the cylinders, operative connection between the valve and one of said rolls, a guide slidably and rotatably supporting the remaining ends of said rolls, a thrust bearing for each roll having a conical recess, the end of the roll being conically shaped in conformity with the bearing recess, a block 80 slidable in the guide in the axial direction of the rolls, means to adjust the position of said block, a pair of levers fulcrumed on said block, and links connecting each thrust bearing to the corresponding ends of the two levers.

7. A self-contained attachment for calendering machines applicable and removable as a unit and designed when co-operating with the calender to cause moiré finishing of cloth passing through the calender, including a pair of cloth directing elements over 90 which cloth may pass into the nip of the calender rolls, the said elements being relatively oppositely reciprocatable in their axial direction, and variable speed mechanical driving means independent of the calendering machine for reciprocating said elements, and framework supporting the elements and driving means.

In witness whereof, I have hereunto set my hand.

JOHN J. LYTH.
